UNITED STATES PATENT OFFICE.

ROBERT T. BOURN, OF TEMPLETON, MASSACHUSETTS.

POST-OFFICE FURNITURE.

No. 902,934.

Specification of Letters Patent.

Patented Nov. 3, 1908.

Application filed February 12, 1906. Serial No. 300,567.

To all whom it may concern:

Be it known that I, ROBERT T. BOURN, a citizen of the United States, residing at Templeton, county of Worcester, and State 5 of Massachusetts, have invented an Improvement in Post-Office Furniture, of which the following description, in connection with the accompanying drawing, is a specification, like letters on the drawings 10 representing like parts.

This invention relates to post-office furniture, and especially to the cabinet or drawer used by the clerk, presiding at the "stamp-window," for holding his stamps, stamped 15 envelopes postal cards, and similar supplies.

In most post-offices several separate drawers are used to keep these supplies, one drawer being used for stamped envelopes or postals; another drawer for stamps in small 20 quantities; another drawer for stamps in sheets; another drawer for the cash, etc.

Where so many different drawers are used more or less time is consumed in opening or closing the various drawers, and the employment of a plurality of drawers is often an 25 inconvenience.

According to my present invention I have improved this class of post-office furniture by devising a drawer which is adapted to 30 hold not only all the various supplies which are usually called for at a stamp-window, in sufficient quantity for even a large post-office, but also the cash received from the sale of the supplies.

In order to make the contents of the 35 drawer more readily accessible I provide a novel form of counter, so constructed that the supplies which are most frequently sold may be taken from the drawer through the 40 top of the counter and without pulling the drawer out.

I will first describe one embodiment of my invention and then point out the novel features thereof in the claims.

In the drawings, Figure 1 is a perspective view of a portion of the counter or desk of a post office where the stamp-window is located showing my improved one drawer system; Fig. 2 is an elevation; Fig. 3 is a detail 50 of the cover for the drawer or removable portion of the counter; Fig. 4 is a top plan of the drawer removed; Fig. 5 is a section in the line $x-x$, Fig. 4; Fig. 6 is a detail of the cover of the counter.

3 designates in general the desk or counter 55 of a post-office, and 4 the "stamp-window."

In accordance with my invention I provide in the counter or desk 3 a single drawer 5 which is especially designed to contain not only all the supplies usually sold from a 60 stamp-window but also the cash received from the sale of said supplies. These supplies usually include stamps of all denominations, both in small quantities and in sheets, stamped envelopes of various sizes, 65 postal cards, stamp-books and stamped wrappers. In order that all these supplies, as well as the cash received from the sales, may be accommodated in a single drawer 5 I make said drawer as follows:— 70

A portion of the drawer is divided by vertical partitions 6 into a plurality of compartments adapted to receive the stamped envelopes, postal-cards, stamp-books, etc.

As I have herein illustrated the drawer 75 these partitions are so arranged as to constitute a compartment 7 for receiving long stamped envelopes, a plurality of smaller compartments 8 for receiving the smaller stamped envelopes, compartments 9 for receiving postal-cards, and smaller compartments 10 for receiving stamp-books of various sizes.

The envelopes and postal cards are arranged on edge in these compartments, and 85 the compartments are large enough to receive three, four or more bunches of each kind of envelopes. These partitions 6 are also so arranged as to form a compartment 11 large enough to receive the cash in the 90 form of bills received from the sale of supplies.

My improved drawer is arranged to receive stamps of the various denominations in strips of five and also in quarter sheets. 95 The stamps in strips are contained in a suitable tray 12, which is preferably arranged at the front of the drawer and which is divided by longitudinal partitions 13 into a plurality of compartments 14, there being 100 one compartment for each denomination of stamps.

The compartments 14 are just wide enough to receive the stamp and are long enough to receive a strip of five stamps. I may, if desired, make two of the compartments of double width so that a double strip of stamps, or ten stamps, may be placed therein. 105

These wider compartments would be used for the one- and two-cent stamps, because stamps of these denominations are very often sold in lots of ten as well as in smaller 5 lots.

The bottom of the tray 12 is curved upwardly at its front edge, as at 15, so that the front end of the superimposed strips of stamps in each compartment may be readily 10 grasped by the clerk and withdrawn from the compartment.

In the present instance of my invention I provide another tray 16 for receiving the cash in the shape of coin. This tray is 15 preferably placed directly back of the tray 12, and is divided by longitudinal partitions 17 into compartments 18 for receiving coin of different denominations.

Both the trays 12 and 16 are preferably 20 removably supported by the drawer. They are of considerably less depth than the drawer and beneath them is a considerable space 19 for storage room.

The stamped wrappers for papers, etc., are 25 received in a compartment 20 which is of a suitable size to receive packages of wrappers flat. This compartment is preferably provided with the false bottom 21, which is shown as hinged to the backside of the 30 drawer, as at 22.

The space 23 beneath this false bottom furnishes ample storage room for packages of stamped wrappers, and the space above 35 said false bottom is ample to receive the broken packages or loose stamped wrappers.

The false bottom 21 is provided at its front edge with a finger-piece or handle 24 by means of which it may be raised when access to the compartment 23 is desired. 40 25 designates stops or supports on which the front edge of the false bottom 21 rests when it is in its normal position. 26 designates a plurality of hinged trays which are adapted to receive the stamps of various 45 denominations in sheets. These trays are shown as being hinged to the backside of the drawer, as at 27, and each is divided by a longitudinal partition 28 into two compartments 29, each compartment 29 being of a 50 size to receive a quarter sheet of stamps.

There are sufficient trays to form a compartment 29 for each denomination of stamp. These various trays are so hinged that the front edge of all the trays are 55 exposed, and the front edge of each tray is provided with a finger-piece 30 so that the contents of any tray may be readily exposed by the turning back of the trays located above it. For instance, if it was desired to 60 take a quarter sheet of stamps from the bottom tray 26 then the next-to-the-bottom tray would be turned back, say next-to-the-bottom tray carrying with it all the trays above it.

65 It will be noted that with the arrange-

ment shown in Fig. 4 the supplies which are most commonly sold, and also the cash, are arranged at the front portion of the drawer. In order to make these supplies and the cash readily accessible without pulling the 70 drawer out I make the top of the desk or counter in a special way, it being cut away, as at 300, see Fig. 1, to expose the front portion of the drawer. A removable closure 31 is provided for covering this opening in the 75 top of the counter or desk and for completing the counter when the drawer 5 is to be locked.

When the clerk comes on duty however he removes the removable cover or closure 31, 80 thus exposing the front portion of the drawer 5 in which the most commonly used supplies are received. When the cover 31 is removed, as described, the clerk may sell small quantities of stamps of all denominations, stamped 85 envelopes of different sizes, postal cards, and stamp-books without pulling the drawer 5 out.

If, however, a sale of stamped wrappers or of stamps in the quarter sheet is made the 90 clerk would be required to pull the drawer out sufficiently to expose the compartment containing these supplies. The amount that the drawer would have to be pulled out however would be comparatively little, as the 95 drawing of the drawer one-third of its length will give access to the compartment containing the stamps in the quarter sheet or the stamped wrappers.

I have so constructed the closure 31 that 100 when it is in place it will lock the drawer 5 from being pulled out. For this purpose it is provided with one or more projections 33 which, when the cover is in place, are received under the edge 34 of the opening in 105 the counter, and it is also provided with projections 35 which enter suitable notches 36 in the false top 37 of the counter or desk. The closure is also provided with the locking projections 38 of any ordinary chest-lock, which projections enter apertures 39 in the front wall of the drawer 5 and are locked 110 therein as usual.

When the closure 31 is in place, therefore, it cannot be drawn forwardly because of the 115 interlocking of the projections 35 and notches 36, nor can the back edge thereof be raised because of the projections 30, nor can the front edge thereof be raised because of the fact that it is locked to the drawer 5. When 120 the chest-lock is unlocked, however, the front edge of the closure may be raised to disengage the projections 35 from the notches 36 when the closure may be readily removed.

In large post-offices two or more stamp-clerks may preside at the same window at different intervals of time, one clerk being there during the morning hours and another clerk during the afternoon and evening for instance.

Where two or more clerks do thus preside at the same window each clerk has his own stock of supplies to sell from; and, therefore, I propose to place in front of each 5 stamp-window 4 two drawers 5 arranged side by side, as shown in Fig. 1. When two drawers are thus used neither drawer is exactly in front of the window, the window being half way between the drawers. With 10 this arrangement I propose to put the trays 12 and 16, which are most used, on the side of the drawer adjacent the middle of the window. The two drawers would, therefore, be arranged as right and left. This, however, 15 is not essential to my invention.

In connection with my improved drawer 5 I propose to make underneath the counter a cupboard arranged for keeping supplies in the bulk. These cupboards are designated 20 by 40 and 41 respectively, and are each adapted to be closed by suitable doors 42. The cupboards may have any suitable interior arrangement. I have herein shown them as provided with various compartments 25 43 adapted for holding boxes of envelopes, and as having a drawer 43 arranged for holding packages of stamps of different denominations, the drawer being of a size to receive the packages on edge. Between the 30 various packages I place a removable partition 45 similar to the dividing partition in an ordinary card catalogue.

The drawer 5 may be made of a size to receive three or four hundred dollars worth 35 of supplies without making it at all bulky or cumbersome to handle. It will thus be seen that with my invention the various supplies sold at a stamp window may be kept in a single drawer and kept in such a way 40 as to be readily accessible, and also in sufficient quantities to meet ordinary demands.

While the arrangement of partitions and compartments in the drawer herein illustrated is that which I deem preferable yet 45 my invention is not limited thereto.

Having described my invention what I claim as new and desire to secure by Letters Patent is:—

1. In post-office furniture, the combination with a desk or counter, of a drawer therein divided into compartments, the portion of the top of the desk at the front edge thereof immediately over the front of the drawer when the latter is closed being 50 removable whereby access to the compartments 55

at the front of the drawer may be had without withdrawing said drawer, and means to lock both said portion of the desk when in place and the drawer when closed.

2. In post-office furniture, the combination with a counter or desk, of a drawer therein having at its front portion coin-receiving compartments and small stamp-receiving compartments, the portion of the top of the desk immediately over the front portion of the drawer when closed being removable whereby access may be had to said coin-receiving and stamp-receiving compartment by removing the removable portion of the top of the desk and without withdrawing 70 the drawer.

3. In post-office furniture, the combination with a counter or desk, of a partition rising from said desk and having a window therein, and a drawer in said counter opposite the window, a portion of the top of the counter immediately over the front part of the drawer when the latter is closed being removable so that access to the drawer may be had without withdrawing the latter. 80

4. In post-office furniture, the combination with a desk or counter, of a drawer therein having at its front portion coin-receiving compartments and stamp-receiving compartments, and at its rear portion a plurality of pivotally-mounted trays, the portion of the top of the desk immediately over the front portion of the drawer when the latter is in closed position being removable whereby access may be had to the coin-receiving and stamp-receiving compartments without withdrawing the drawer. 85

5. In post-office furniture, a counter or desk having a top, a drawer slidably mounted in the desk beneath the top and divided 95 into a plurality of compartments for receiving coins and supplies of different character, a portion of the top of the desk being cut away to expose a portion of the drawer, a removable closure for the top of the desk, 100 and means to lock the removable closure both to the drawer and to the desk or counter.

In testimony whereof, I have signed my name to this specification, in the presence of two subscribing witnesses.

ROBERT T. BOURN.
